UNITED STATES PATENT OFFICE.

MATO FITZMAURICE MALONEY, OF ATLANTIC BEACH, FLORIDA.

HAT-HOLDER.

1,213,392.

Specification of Letters Patent.

Patented Jan. 23, 1917.

Application filed July 17, 1916. Serial No. 109,746.

To all whom it may concern:

Be it known that I, MATO FITZMAURICE MALONEY, a citizen of the United States, residing at Atlantic Beach, in the county of Duval and State of Florida, have invented certain new and useful Improvements in Hat-Holders; and I do declare the following to be a full, clear, and exact description of the invention, such as will enable others skilled in the art to which it appertains to make and use the same.

This invention relates to new and useful improvements in devices for suspending articles of clothing when not in use, and has special reference to hats and caps, and the primary object of the invention is to provide a simple and compact article, that when not in use, may be easily carried from place to place.

Another object of the invention is to provide a device of this character which is easily and simply constructed, inexpensive to manufacture, and one which will be very efficient in operation.

With these and numerous other objects in view, my invention consists in the novel features of construction, combination and arrangement of parts which will be herein referred to and more particularly pointed out in the specification and claim.

In the accompanying drawings:—Figure 1 is a side elevation of the holder; Fig. 2 is an enlarged front elevation of the same; Fig. 3 is a vertical section taken on the line 3—3 of Fig. 2; and Fig. 4 is a detail front view of the section cup.

In describing my invention, I shall refer to the drawings in which similar reference characters designate corresponding parts throughout the several views and in which the numeral 1 designates a stationary jaw that comprises the base of my holder, and which is provided with raised side portions 2 intermediate its ends. These raised side portions 2 are provided adjacent their forward end with a transversely extending pivot pin 3 secured in the opposite sides, while adjacent their rear ends and contiguous the jaw, are alining openings 4 for a purpose to be hereinafter more fully described.

The forward portion of the stationary jaw 1 is provided with an upwardly projecting flange 5, which extends around the same and adjacent the extremity of said front portion of the jaw are upstruck lugs

6, that are adapted to securely hold a rubber pad 7 in the jaw adjacent the extremity. This pad 7 projects a slight distance above the upper edge of the flange 5, and affords 60 a protection for the article secured between the jaws of the device when in operation.

The opposite end of the jaw 1 is bent hook-shaped as shown at 8, so that this holder may be held supported in various places. 65 This hook-shaped end is an integral part of the stationary jaw, and when it is found desirable to fix the holder in a certain position, may be secured to the support in which it is positioned.

The holder is provided with a movable jaw 9, which has large side portions 10 adjacent its inner end that are positioned between the side portions 2 of the stationary jaw, and have alining openings 11 therethrough through which the pivot pin 3 is positioned. By this means, the jaw 9 will be pivotally mounted with respect to the stationary jaw 1, and the outer end of the same will be adapted to move toward and 80 from the outer end of the jaw 1. The inner end of the movable jaw 9 is provided with a transversely extending recess 12 therein for a purpose to be hereinafter more fully described.

The movable jaw 9 is provided with a projecting flange 13 around its edge, and adjacent the outer end of this flange 13 are inwardly projecting lugs 14, that are adapted to securely engage the edges of a rubber 90 cap 15 positioned in a socket 16 formed in said end of the jaw. This rubber cap 15 will facilitate the holding of an article between the jaws, without injuring the same. Mounted on the pivot pin 3 is a coil spring 95 17 so arranged that the movable jaw 9 will be normally held open, and away from the fixed or stationary jaw 1.

The movable jaw 9 is operated by a crank lever 18 that is provided with laterally projecting lugs 19 on opposite sides of its bent portions, that are adapted to be positioned through the alining openings 4 in the side portions 2 of the stationary jaw. This crank lever is positioned as clearly shown in Figs. 100 2 and 3 of the drawings, and it will be obvious that upon operation of the same, the outer end of the movable jaw will be moved toward and from the stationary jaw.

When the parts of this holder are positioned as shown in Fig. 1 of the drawings, the movable jaw will be positioned away

from the fixed jaw, and an article, as for instance the brim of a hat, may be inserted between these jaws. The crank lever 18 is then moved downwardly toward the fixed jaw 1, whereupon its bent end will engage the inner end of the movable jaw and rock the same so that its outer end will be forced inwardly toward the fixed jaw, thereby securely locking the hat brim therebetween. When the bent end of the crank lever reaches a point adjacent the extremity of the inner end of the movable jaw, it will drop into the transversely extending recess 12, and will securely lock the parts.

The rubber pad on the fixed jaw will prevent any injury to the hat brim, while the rubber cap on the movable jaw will form an air chamber that will form an additional locking means to hold the hat brim in position. Owing to the fact that this holder is such a small compact device, the same may be easily carried from place to place. Its use will be found especially advantageous in churches, motion picture shows, trains, dining rooms, and other places where the user desires to hang his hat in some convenient place where it will be out of the way. This device may be hooked over the front of a pew or seat and the hat secured between its jaws will be held until needed. Upon disengagement of the hat, the article may be placed in the user's pocket and easily carried, owing to the fact that it will occupy

very little space. The pin holes in the handle are for ladies' hat pins to hold the same 35 in position.

From the foregoing description, the construction and operation of this garment holder, the manner of applying the same to use and the operation thereof will be readily 40 understood, and it will be seen that I have provided a simple and efficient means for carrying out the objects of this invention.

I claim:—

A device of the class described comprising 45 a short jaw and a long jaw having a pivoted connection with each other, and a spring coil coacting with the jaws to normally hold them open, a flat pad on the lower end of the long jaw, a recessed pad 50 on the lower end of the short jaw, the long jaw having a locking lever pivoted thereto above the common pivot of the jaws, said short jaw having a transverse groove adjacent its upper end, and a free end of the 55 locking lever adapted to engage the upper end of said short jaw and to be positioned in the transverse groove to positively lock the jaws in closed position.

In testimony whereof I have hereunto set 60 my hand in the presence of two subscribing witnesses.

MATO FITZMAURICE MALONEY.
